(74) Attorney, Agent, or Firm — Orbit IP, LLP

(57) **CLAIM**

The ornamental design for an electric toothbrush, as shown and described.

DESCRIPTION

FIG. 1 is an isometric view of an electric toothbrush illustrating my new design;

FIG. 2 is a front elevation view thereof;

FIG. 3 is a right-side elevation view thereof;

FIG. 4 is a back elevation view thereof;

FIG. 5 is a left-side elevation view thereof;

FIG. 6 is a top plan view thereof; and,

FIG. 7 is a bottom plan view thereof.

The broken lines in the drawing figures illustrate features of the article of manufacture that form no part of the claimed design.
